BOILER CASING

Lawrence N. Janis, Chicago, Ill., assignor to Triad Products Corporation, Chicago, Ill., a corporation of Illinois

Application January 17, 1955, Serial No. 34,010

Term of patent 7 years

(Cl. D81—2)

Fig. 2

Fig. 3

The side of the casing not shown is substantially like the side shown.

Fig. 1 is a perspective view of a boiler casing embodying my new design.

Fig. 2 is a top, plan view of a boiler casing.

Fig. 3 is a section along the line 3—3 in Fig. 1.

I claim:

The ornamental design for a boiler casing as shown and described.
